UNITED STATES PATENT OFFICE.

WILLIAM S. COLWELL, OF PITTSBURG, PENNSYLVANIA, ASSIGNOR TO THE TRIPLE THERMIC MOTOR COMPANY, OF NEW YORK, N. Y.

TRIPLE THERMIC MOTOR.

SPECIFICATION forming part of Letters Patent No. 313,179, dated March 3, 1885.

Application filed August 21, 1884. (No model.)

To all whom it may concern:

Be it known that I, WILLIAM S. COLWELL, of Pittsburg, in the county of Allegheny and State of Pennsylvania, have invented a certain 5 new and useful Improvement in Triple Thermic Motors; and I do hereby declare that the following is a full, clear, and exact description thereof, reference being had to the accompanying drawings, and to the letters of reference 10 marked thereon.

My invention consists in the combination of devices, hereinafter described and specifically claimed.

To enable others skilled in the art with 15 which my invention is most nearly connected to make and use the same, I will proceed to describe its construction and operation.

In the accompanying drawings, which form part of this specification, Figure 1 is a side 20 elevation of my improvement in a triple thermic motor. Fig. 2 is a vertical section of the regulating-valve used in connection with said motor. Fig. 3 is a side elevation of said valve. Fig. 4 is a vertical section of the regulating- 25 valve used for controlling the pressure of steam in the casing which surrounds the conduit for the bisulphide-of-carbon vapor and the casing surrounding the cylinder of the engine. Fig. 5 is a side elevation of the same. 30 Fig. 6 is a vertical section of a washer used in connection with said motor.

Reference being had to the accompanying drawings, A represents an ordinary steam-boiler, provided with the usual appendages, 35 and is provided with a conduit, B, which communicates with the regulating-valve C, (see Fig. 2,) which consists of two chambers, a b, secured together, with a non-conducting packing, c, placed between them—such as asbestos—for preventing the heat from chamber 40 b being transmitted to chamber a.

The chamber a is provided with a plunger, d, connected to a pivoted lever, e, having an adjustable weight, f. The lower end of the 45 plunger d is of the form of a section of a sphere, which form will prevent the plunger from cutting or otherwise injuring the elastic diaphragm g, which divides the chamber a into two compartments.

The chamber b is furnished with a balance-valve, h, and suitable seats for said valve.

The stem i of this valve is connected to the lever e. To the chamber b is connected the pipe B, which communicates with the steam-boiler A.

To the chamber a is connected a pipe, k, which communicates with the vapor-space of the bisulphide-of-carbon boiler F, and is provided with a valve, l, above which said pipe is filled with water. The weight f being adjusted on the lever e for securing the desired pressure of the bisulphide-of-carbon vapor in the boiler F and the desired admission of steam to and through said boiler for evolving said vapor, steam flowing through pipe B 65 from boiler A enters the chamber b of the regulating-valve C, and passes therefrom through the pipe D to and through the boiler F. The vapor of bisulphide of carbon passes from the boiler F, filling the pipe k, in which 70 it condenses until it fills the pipe to about the dotted lines x. The valve l now being opened, the bisulphide-of-carbon vapor will press against the water, which, pressing against the elastic diaphragm g, and it against the plunger 75 d, which, in combination with the lever e and weight f, will open and close the valve h in accordance with the pressure in the bisulphide-of-carbon boiler F, closing said valve when the pressure is greater than that fixed 80 upon, and opening it when it is less, thereby diminishing the flow of steam through the pipe D when the pressure of the bisulphide-of-carbon vapor is greater than that determined upon, and increasing said flow when it is less, 85 thereby increasing and diminishing the heat around and through the bisulphide-of-carbon boiler F, whereby the desired working-pressure of the vapor is always maintained.

The pipe A' communicates with the pipe B 90 and the regulating-valve K, which is constructed in every respect the same as the regulating-valve C, excepting the pipes n and o, the latter of which communicates with the casing I, which surrounds the pipe H, which 95 conducts the vapor of bisulphide of carbon to the cylinder of the engine J.

The operation of the valve K is the same as that of the valve C, excepting that the steam which enters it also controls the movements of its valve and plunger for controlling the admission of steam into the case I, by adjust-

ing the weight q of the lever r for obtaining the desired pressure of steam in the case I, which pressure may be indicated by a gage, as at B'.

5 The operation will be as follows: The steam, flowing from the boiler A through pipes B A', enters the chamber M', and from it, through pipe o, enters the case I, which communicates with the casing of the cylinder of the engine J, so that the same pressure of steam which is in case I will also be in the casing of the cylinder of the engine. In the event of the pressure in the boiler A increasing beyond that determined upon for the case I, the pressure of steam will act against the diaphragm g' , which acting the plunger d' will thereby, through the medium of the lever r and weight q , so operate the valve h' as to cut off or partly cut off the supply of steam to case I till the desired pressure is attained in said case. If the pressure in the casings should become less than that fixed upon, then the weight q , through the medium of the lever r , will open the valve h' , so as to admit more steam, and will hold the valve open till the desired pressure is attained. It will be observed that by this arrangement of the regulating-valve K with relation to the casing I, and it communicating with the casing of the cylinder of the engine J, uniform pressure may be maintained in said casings notwithstanding any variation of pressure that may occur in the boiler A, and that the heat, and consequently pressure, in said casings is greater than that in the casing E of the bisulphide-of-carbon boiler F, and that the vapor in the pipe H and in the cylinder of the engine is subjected to an increased heat, which increases the tension after it leaves the boiler F until it performs its office upon the piston of the engine J.

In the operation of the steam-engine from the moment the steam leaves the boiler and its furnaces or superheater until it reaches the piston of the engine there is a continuous loss of its heat, and therefore a corresponding loss of power, and when working steam expansively there is a further loss of heat and power due to the steam coming in contact with the walls of the cylinder, which are of less temperature than the steam; but in working the vapor of bisulphide of carbon, as herein described, the vapor is superheated from the time it leaves the generating-boiler F until the end of the stroke of the piston of the engine, the vapor being subjected after leaving the boiler to a greater temperature in the pipes and cylinder than that at which it was evolved in the boiler F. It therefore follows that in working it expansively it can be cut off at an earlier point in the stroke of the piston, and in view of these facts economy of fuel, heat, and a full utilization of the power generated in the boiler follow.

For the purpose of showing the gain secured by this arrangement for subjecting the vapor to a greater heat than that at which it was generated in the boiler F, I give the following ex-

ample: When the pressure of steam in the boiler A is about fifty (50) pounds per square inch of boiler-surface, and the circulating pressure of the steam around and through the boiler F is six (6) pounds per square inch of boiler-surface, (working-pressure.) the bisulphide of carbon in the boiler F will be subjected to about 230° of heat, Fahrenheit, which will evolve the bisulphide of carbon into a vapor having a working-pressure of sixty-eight (68) pounds working-pressure per square inch of boiler-surface. Now, with about forty-three (43) pounds working-pressure in the casing I and in the casing of the cylinder of the engine J, the bisulphide of-carbon vapor, after leaving the boiler F, will be subjected to an increased heat of sixty-three (63) degrees more than it was in the boiler F, therefore requiring a less quantity of vapor to be withdrawn from the boiler F for the purpose of working the engine J.

When it is desired to work the vapor expansively the engine is provided with any known "cut-off" mechanism. The vacuum-pump R communicates with the condenser M and with the washer S, which latter device (see Fig. 6) consists of a shell, s, with a pipe, t, having a valve, u, said pipe communicating with the vacuum-pump R and projecting down into the shell below the water-line (indicated by dotted line v,) at which point is a waste-pipe, w. To the upper end of the shell s is attached a pipe, y', for carrying off the washed air and incondensable and unabsoed gases. The shell s is also provided with a pipe, a', for supplying it with water, and also drain-pipes b' c', and with a "sight-gage," d', for showing the height of water in the shell s. The piston and valve rods are provided with packing-chambers, which through the medium of the pipe s' with well N, which communicates with the condenser M and vacuum-pump R, which arrangement and combination of parts will prevent the vapor of bisulphide of carbon leaking out into the engine-room, the tendency of the atmosphere being toward the joints around the piston and valve rods. By this combination of parts, in connection with the exhaust-ports of the engine J, communicating by pipe y with the heater L, condenser M, well N, and vacuum-pump R, it will be apparent that it will be impossible for any of the vapor of bisulphide of carbon to escape into the engine-room or be wasted. The hot-water pump O, which supplies the boiler A with hot water, the product of the condensed steam, which product is conveyed to the pump through the medium of pipes communicating with the several compartments supplied with steam from the boiler A, is the same as that described in Letters Patent No. 266,952, granted to me October 31, 1882.

It was discovered that in the working of the pump (marked D in the drawings of said patent) it did not at all times work perfectly in the pumping of the hot-water when it was at or about the boiling-point. To remedy this

defect, a pipe, e' , is employed, so as to communicate between the casing of the boiler F and the pump O, to convey steam therefrom, which means causes said pump to do its work successfully at all times. I state this fact, which has been fully demonstrated by an experience of several months' use of said arrangement, without attempting to describe its theory of operation.

10 The operation of my improvement, briefly stated, is substantially as follows: Steam is generated in the boiler A, which, by means of a pipe provided with a reducing-valve, communicates with a boiler, F, and by the heat of 15 the steam at a low degree of pressure the bisulphide of carbon is evolved into a vapor, which is conveyed by pipe H to the cylinder of the engine, the vapor being superheated in said pipe by steam from the boiler A at a 20 higher pressure, and consequently a higher degree of temperature. After the vapor has performed its office in the engine-cylinder it is exhausted and conducted to the condenser M by gravity, assisted by the vacuum in the 25 condenser. Passing through the heater L on its way to the condenser, the exhaust-vapors impart their heat to the liquid, being returned from the well N through the heaters L and T into the boiler F by pump P.

30 The vacuum-pump R forms a vacuum in the condenser M and well N by withdrawing air and gases from them and forcing said air and gases through pipe t down into the water in the washer S, thereby washing said air and 35 condensing the condensable gases, the washed air and incondensable gases passing off through the pipe y' , and any bisulphide of carbon which may be collected in the washer S can be drawn off by means of the pipe b' , and thereby be 40 saved.

The methods involved in generating a motor from liquid bisulphide of carbon embodied in my invention are claimed in my application No. 138,819, filed July 26, 1884, of which 45 this is a division.

Having thus described the construction and operation of my improvements, what I claim is—

1. The combination of a heat-generator, a 50 vapor-generator, means, substantially as described, for applying heat to the vapor-generator, a vapor-conduit, and a superheating or expanding chamber in which a higher degree of heat is applied to the vapor and continued until the vapor has been utilized in an 55 engine-cylinder, substantially as described.

2. The combination of a steam-generator, a vapor-generator, a chamber surrounding the vapor-generator, a conduit for supplying steam 60 to said chamber at a low temperature, and an automatic pressure-reducing valve operated by the vapor acting upon one end of a column of liquid and the gravity of a suspended weight upon the other end, substantially as described.

65 3. The combination of a steam-generator, a vapor-generator, means, substantially as described, for applying heat thereto at a low tem-

perature, a vapor-superheating conduit, and a valve for controlling the supply of steam at a higher temperature to the chamber surrounding said conduit, substantially as described.

4. The combination of a steam-generator, a vapor-generator, means, substantially as described, for applying steam at a low pressure to liquid bisulphide of carbon to evolve vapor, 75 a conduit for conducting the vapor to the engine and superheating the same, and a valve for controlling the supply of steam at a higher pressure to a chamber surrounding the conduit and a jacket around the working-cylinder, substantially as described.

5. The combination of a steam-generator, a vessel containing liquid bisulphide of carbon, means, substantially as described, for applying steam thereto at a low temperature for 85 evolving vapor, a superheating-chamber, and an automatic valve for supplying steam at a higher temperature to said expanding-chamber and to a jacket around the working-cylinder, substantially as described.

6. The combination of a steam-generator, a vapor-generator, means, substantially as described, for applying steam at a low pressure to evolve vapor from liquid bisulphide of carbon, a conduit for superheating the vapor with 95 steam direct from the steam-generator, and a relief-valve for returning any excess of vapor to the condenser, substantially as described.

7. The combination of a steam-generator, a vapor-generator containing liquid bisulphide 100 of carbon, means, substantially as described, for evolving vapor therefrom by applying steam at a low pressure, a conduit for conveying the vapor to an engine and superheating the same, a valve for controlling the supply 105 of vapor to the conduit, and a steam supply-valve for controlling the steam from the generator to the chamber surrounding the conduit, substantially as described.

8. The combination of a steam-generator, a vapor-generator containing liquid bisulphide 110 of carbon, means, substantially as described, for evolving vapor therefrom, an automatic pressure-reducing valve, a conduit for conducting the vapor to the engine and super- 115 heating the same, an automatic valve for controlling the supply of steam to the chamber surrounding the conduit, and a valve for controlling the supply of vapor to the conduit, substantially as described.

9. The combination of a steam-generator, a vapor-generator, and means for applying heat thereto at a low temperature to evolve a vapor from liquid bisulphide of carbon, a conduit for conducting the vapor to the engine, a 125 chamber surrounding the conduit, a pressure-reducing valve for supplying steam to the vapor-generator operated by the vapor contained in the generator acting upon one end of a column of liquid and the gravity of a weight upon the other end, and a valve for controlling the supply of steam direct from the generator to the superheating-chamber at a higher temperature operated by the pressure of steam 130

in said chamber and the gravity of a suspended weight, substantially as described.

10. The combination of a steam-generator, a vessel in which liquid bisulphide of carbon is evolved into vapor by the application of heat at a low temperature, a conduit in which it is superheated under heat of a higher temperature automatically supplied and continued throughout the working stroke of the engine, 10 a valve for controlling the supply of vapor to the conduit, and an automatically-operated valve for supplying the engine and cutting off the supply, substantially as described.

11. The combination of a steam-generator, 15 a vapor-generator containing liquid bisulphide of carbon evolved into vapor at a low temperature and superheated under a higher temperature by the application thereto of steam direct from a steam-generator, an engine in 20 which the energy of the vapor is applied, and a condenser to which the exhaust is returned, substantially as described.

12. The combination of a steam-generator, a vapor-generator containing liquid bisulphide 25 of carbon evolved into vapor at a low temperature and superheated at a higher temperature by steam from the generator, said expansion being maintained above its initial expansion until its power has been applied to an engine, 30 a condenser, and a washer into which the air which may be contained in the condenser charged with uncondensed vapor is conducted, substantially as described.

13. The combination of a steam-generator, 35 a vapor-generator containing liquid bisulphide of carbon, means, substantially as described, for evolving vapor therefrom under a low degree of heat and superheating the vapor under a higher degree of heat automatically controlled and maintained during the stroke of the engine-piston, a condenser, and a vacuum-pump whereby the exhaust-vapor is returned to the condenser by gravity, substantially as described.

45 14. The combination of a steam-generator, a vapor-generator containing liquid bisulphide of carbon evolved into vapor by the application of heat at a low temperature and superheated by heat at a higher temperature automatically supplied and maintained until the 50 power thereof has been applied to an engine, a condenser, a reheater, and a pump for returning the liquid bisulphide to the vapor-generator at nearly the temperature at which it is evolved into vapor, substantially as described.

55 15. In a bisulphide-of-carbon engine, the combination of the condenser, the vacuum-pump, and the washer partly filled with water, substantially as described.

16. In a bisulphide-of-carbon engine, the washer partly filled with water, a dip-pipe projecting into the water, a receptacle for the precipitated liquid bisulphide of carbon, an outlet for said liquid, and an escape-pipe for the air into the open atmosphere, substantially 65 as described.

17. In a bisulphide-of-carbon engine, the combination of the condenser, the well, the washer, the vacuum-pump, and the liquid-pump for returning the liquid bisulphide 70 to the vapor-generator, substantially as described.

18. In a bisulphide-of-carbon engine, the combination of a steam-generator, a vapor-generator, and conduit for conducting the vapor to the engine, the chambers surrounding the vapor-generator, the conduit, and the cylinder, and means, substantially as described, for conducting steam to said chambers and returning the water of condensation with a volume of steam from the chamber surrounding the vapor-generator to a pump for returning said water to the steam-generator, substantially as described.

19. In a bisulphide-of-carbon engine, the combination of the engine, its exhaust-ports, the chamber surrounding the piston and valve-rods, the condenser, and a vacuum-pump, substantially as described.

20. In a bisulphide-of-carbon engine, the combination of the chambers surrounding the piston and valve rods, the condenser, and a vacuum-pump, substantially as described.

21. In a bisulphide-of-carbon engine, the valve for controlling the supply of steam to the vapor-generator, which consists of a balanced valve, a piston and diaphragm, suitable intermediate connections, and a suspended weight, in combination with a pipe containing a column of water interposed between the diaphragm and the vapor contained in the vapor-generator, substantially as described.

22. In a bisulphide-of-carbon engine, the valve for controlling the supply of steam in regulated quantities and at a predetermined pressure to the chamber surrounding the vapor-conduit, which consists of a balanced valve, a piston, a diaphragm, and suitable intermediate connections, in combination with a pipe connecting with said chamber to admit steam to the diaphragm to move the valve in one direction, and a lever and a suspended weight to return the valve to its normal position, substantially as described.
